KNITTING MACHINE

Roy C. Amidon, Reading, Pa., assignor to Vanity
Fair Mills, Inc., Reading, Pa., a corporation of
Pennsylvania

Application January 20, 1944, Serial No. 519,015

3 Claims. (Cl. 66—86)

My invention relates to knitting machines, and particularly to machines of the Tricot type.

More specifically, the present invention relates to mechanism for feeding or delivering the thread or yarn, used in the knitting process, from the warp beams to the needles. In the production of fabrics made upon the Tricot or so-called fast-warp machines, or in any process using the fast-warp principle, the density of the fabric or tightness of the stitches is largely determined by the feeding (portion of yarn allotted to each knitting cycle).

In warp knitting machines the thread or yarn is initially wound on one or more warp beams and is passed from the beams, through thread or 15 yarn guides that are carried by the guide bars of the machine, to the needles.

In order to control the turning movement of the beams it has been found necessary to provide a brake or clutch system regulated by the movement of a tension rod over which the threads or yarns pass and which is actuated by the draw of the warp thread or yarn as the guides place the same around the needles and in the knock-over of the stitch in the knitting process.

It has already been proposed to drive the warp beams with a continuous drive; nevertheless the use of a tension device is necessary in this case also to take up the slack as released by the rotating warp beam during the time, in the knitting cycle, when no thread or yarn is being used by the guides and/or by the needles in the knock-over process. The use of spring-loaded tension rods is not always uniform over the entire width of the machine at various speeds of the machine.

Any stopping or starting of the machines heretofore in use, with which I am familiar, produces an irregularity in the knitting operation, resulting in the formation of an undesirable line or streak, called a "stop-mark" in the fabric.

My invention, therefore, has for its general object to overcome the objectionable features of the machines above referred to.

More specifically, my invention has for an object to provide an intermittent drive for each warp beam to turn the beam in timed relation to the thread or yarn consumption during the knitting cycle and cause it to discharge or release the thread or yarn in the correct proportion and at the correct or proper times, and to do this regardless of the changing circumference or diameter of the beam as the knitting function proceeds.

Again it is an object of the invention to provide a simplified form of the invention disclosed

in my application Serial #516,777 filed Jan. 1, 1944.

Other objects of the invention will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a front elevational view illustrating my invention.

Fig. 2 is a detail end elevation of a portion of the structure shown in Fig. 1.

Fig. 3 is an enlarged detail vertical longitudinal section on the line 3—3 of Fig. 4.

Fig. 4 is a horizontal section on the line 4—4 of Fig. 3.

Fig. 5 is a detail horizontal section on the line 5—5 of Fig. 1.

Figs. 6 to 9 inclusive are diagrammatic views hereinafter specifically referred to.

In the drawings, in which like numerals and letters of reference indicate like parts in all the figures, 1 represents the main frame of the machine. This frame includes the uprights 3, the top cross arm 5, and the slide-bearing member 7. The member 7 has an opening 8, into which the gears 18 project, and has vertical grooves 9 for the racks 66 of a rack-bar 65 later again referred to. The frame also includes a mounting flange 2 through the medium of which, and cap screws or bolts, the frame is mounted on an end frame 10 of a knitting machine. The frame 1 has a slot 4 and shaft bearings 6, 6', and recesses 10 to receive the hand wheel 46, later again referred to.

Mounted in bearing apertures 101 and 102 in the main frame is a first vertical driving shaft 38.

A second vertical driving shaft 40 is journaled in bearings 103 and 6' in that frame. The shafts 38 and 40 are operatively connected together to turn at the same speed by means of herringbone gears 45, best shown in Fig. 1. The shafts 38 and 40 have fluted portions 39 and 41, respectively, on which the driving friction wheels are slidably held, as will later be more fully explained.

Mounted in suitable bearings 15 are parallel shafts 11 and 12, respectively, which shafts are geared together by suitable gears 13 and 14. These shafts are mounted in bearings 15 and 16.

The shafts 11 and 12 carry pinions 18 which project into the openings 8 in the bearing or

guide 7 and engage the racks 66 of the bar 65. The shafts 11 and 12 carry pinions 17 which mesh with the racks 26 that are carried by the uprights 24 of the carriage-engaging plates 23. These plates 23 are secured to the carriage by cap screws 25.

The uprights 24 of the plates 23 on one side of the frame are connected to those on the opposite side by blocks 24'.

The sliding carriage comprises the front plate 19 and back plate 20 between which spacing blocks 21 are secured. A bearing block 22 is also secured between the plates 19 and 20 (see Figs. 1, 3, and 4).

The friction wheel carrier is composed of the pairs of arms 29 connected by horizontal bars 33 and secured at their lower ends to the base blocks 30. The blocks 30 carrying upstanding blocks 31 which are bored and tapped, as at 32, to receive the adjusting screws 49, the screws 49 being mounted in bearing apertures 51 in the block 22 and having gears 50 which mesh with a third gear 48 on a stub shaft 47 also journaled in the block 22, as best shown in Fig. 3. Cap screws 34 pass through the slots of the arms 29 into the carriage.

Suspended rigidly from the upper base member 30, by bars 37, is a lower base member 36. The driving friction wheels 42, wear discs 43 and spacers 44 are located between the upper and lower base members 30 and 36 respectively.

Mounted on a shaft 55, that is journaled in bearings 6 and 12, is a driven friction wheel. The driven friction wheel may comprise two metal discs 52 located between a resilient disc 53 (rubber for example) which tends to maintain good contact at all times between the friction wheels. Cross-connecting pins 54 may be provided to tie the discs 52 and 53 together. Collars 57 on the shaft 55 and a key 56 serve to secure the driven friction wheel to the shaft 57 (see Figs. 1 and 3).

The beam shaft 61' and spool 61 are coupled, as at 62, to a shaft 58 which is mounted in a bearing 71 and is driven through herringbone gears 59 and 60 from the shaft 55.

The rack bar 65 carries a beam-contacting roller 63, mounted in a fork 64. It will be observed that the rack bar 65 moves up and down vertically along a radius of the beam and the axes of the several shafts 38, 40, 55, 58, and those of the beam and roller and also the rack bar all lie in the same vertical plane, the ideal positions for accurate adjustments and functioning of the apparatus.

Referring now more particularly to Figs. 1 and 2, it will be seen that the shaft 38 is connected through a variable speed transmission 116, with a shaft 117 that carries a toothed wheel 67 which meshes with an interrupted flange 77 on a hub 76 having a clutch member 74 rotatably mounted on the cam shaft 73 (or any other constantly movable suitable shaft of the knitting machine). The member 74 may be mounted to turn on the shaft 73, but not be slidable thereon, by means of a pin and groove connection 75. A bracket 68 is mounted on the end frame 70 and is provided with a bearing 69 for the end of the cam shaft 73. A shiftable clutch member 80 is keyed to slide on the shaft 73 and is normally held in engagement with the clutch member 74 by a spring 81 held by a collar 82 adjustable on the shaft. The member 80 may be shifted out of engagement by means of a forked lever 83 and pull bar 84, the latter having a notch 86 to engage the slotted bracket 85 through which the rod 84 75

passes and latch the clutch in the non-operative position.

The interrupted flange 77, meshing with the teeth of the toothed wheel 67, has a curved or worm portion 78 of a suitable pitch—say enough to move the toothed wheel one tooth for each revolution of the shaft 73. The flange 77 may also have another curved portion 79 which may terminate in a straight end 79' which lies in a plane offset from that of the uncurved part of the flange 77, or it may curve back and terminate in the same plane as the uncurved part of the flange, as shown, respectively, in Figs. 7 and 9 and hereinafter more fully explained.

The variable speed transmission between shafts 117 and 38 is preferably one of the Reeves type shown, although any other suitable type may be employed. This transmission includes the supporting frame secured to end frame 70 by a bracket 125, the driving discs 119 slidably keyed to shaft 117, the driven discs 118 slidably keyed to shaft 38, the driving belt 120, the disc shifting levers 121, the adjusting screw 122 with hand wheel 124, and the indicator 123.

As best shown in Figs. 1 and 3, a sprocket 87 is mounted on the shaft 12. A bracket 89 is secured to the frame 1 and carries a stub shaft 90 on which is mounted a hand wheel 91 and sprocket 92. A chain 88 takes over the sprockets 87 and 92 for a purpose later to be made clear. The sprocket 92 is secured to turn with the hand wheel 91 by a set screw 93.

In Figs. 6 and 8, 94 indicates the rock-shaft which carries the thread guide 96 and racking bar 95 of the knitting machine, while 97 indicates a stationary thread guide bar, 98 a knock-over sinker and 99 a needle of the machine, while 100 indicates the thread or yarn. Figs. 6 to 9 are diagrammatic views soon again to be referred to.

The adjustable mounting of the friction wheel carrier on the sliding carriage, in the present embodiment is provided simply for convenience in making a fine initial adjustment of the position of the wheels 42 on the driven friction wheel 52, 53 and may be omitted if desired in which event the friction wheel carrier will be fixedly secured to the sliding carriage in any well known or convenient way.

Operation

Assume the parts to be positioned as shown in Figs. 1, 2, and 3. Each rotation of the shaft 73 will turn the toothed wheel 67 the distance of one tooth, which, with the setting of the friction and change-speed gearing as shown, will advance the beam the distance required to feed off enough thread or yarn as is required for one course of the knitting. Movement of the shaft 117 is transmitted to shaft 38. From thence motion is transmitted to shaft 55, through the friction drive 42, 52—53 and from shaft 55 to the beam shaft 61' through the herringbone gears 59, 60. The change in the positions of the friction wheels 42 with respect to the friction wheel 52—53 varies in proportion to the decrease in the diameter of the beam as the thread is taken off.

If it is desired to lengthen or shorten the feed of thread to the needles for different knitting, the hand wheel 124 is turned to decrease or increase the speed of shaft 38 accordingly.

In the knitting process thread is laid about the needles by the thread guide or guides and on the down strokes the needles draw the thread through previously formed and knocked-over loops, there being periods of dwell during which no thread is

being drawn from the beam. Depending on the way the thread guides are mounted, i. e., the way they move from front to back of the needles in laying the thread, the guides pull more or less of the thread in addition to the pull of the needles. This makes it necessary, in knitting machines generally, to provide yieldably thread tensioning guides. My invention has been designed to do away with the resilient guides and provide a positive thread feed at all times. For example: if the thread guides 96 are so mounted as to swing back and forth and rack the thread about the needle without a backlash of the thread, then I provide a flange 77 with a deflection 79 sufficient to move the beam just far enough to allow the thread guides 96 to function while keeping the thread taut or under a constant tension, the end of the deflected portion 79 terminating to one side of the general plane of the dwell portion of the flange (see Fig. 6); if, however, the movement of the thread guide 96 results in a pull and a slack on the thread, then the deflected portion 79 terminates in the same plane as the dwell portion of the flange or as near thereto as necessary to reverse the beam movement to take up the slack.

The use of herringbone gears 45, 59 and 60, and the use of anti-friction bearings (not shown) wherever possible will prevent backlash or looseness in the transmission between the shaft 38 and the beam, as well as prolong the life of the same.

When it is desired to insert a new beam in place of an empty one, the clutch 80 is thrown out and the wheel 91 is turned to lift the beam-engaging roller out of the way. After the beam has been replaced with the full beam, the wheel 91 is reversed until roller 63 again rests on the thread 100.

It should be understood that when more than one beam is used in a knitting machine, my apparatus will be duplicated accordingly, i. e., one device will be provided for each warp beam.

Attention is called to the fact that the expandable friction wheel 52—53 gives a flexible contact with the driving wheels 42 and prevents slippage. Further, the outer surfaces of the discs 52 may be roughened or milled to aid in preventing slippage.

With my invention in use, a formula may be set up which will produce the same degree of tightness or density of stitches at all times in any given width of fabric, for the reason that the output of warp thread or yarn is positive and is delivered to the guides and needles of the knitting machine in the same amounts as are used by the guides and needles while performing their knitting cycles; the output of warp thread is not dependent upon any cam or spring action between the warp beam and the needles during the knitting process.

In the manufacture of knitted fabrics, when more than one warp beam is used, the rate of the discharge of the threads or yarns from the several beams, in relation one to another, is very important, as fabrics of different degrees of density or elasticity are in demand for different purposes.

By the use of my invention, changes may be made by simple adjustments of the several warp beam operating units whereby positive alterations may be made to change the degree of density or elasticity of the knitted fabric, as may be desired.

From the foregoing description, taken in connection with the accompanying drawings, it is

thought the complete construction, operation and advantages of my apparatus will be clear to those skilled in the art to which it appertains.

What I claim is:

- 5 1. In a knitting machine wherein is provided knitting needles, thread guides for laying thread about the needles, a beam and a constantly rotating shaft; the improvement which includes a support; a pair of parallel shafts rotatable in said support; meshing gears on said pair of shafts; a step-by-step power transmission including a variable-speed transmission mechanism between said constantly rotating shaft and one of said parallel shafts; friction wheels slideable on and rotatable with said parallel shafts; a third shaft mounted in said support; a friction disc on said third shaft; power transmitting connections between said third shaft and said beam; a sliding carriage for said friction wheels; a member for 10 resting on the thread of the beam and movable along a radius of the beam; and operative connections between said member and said sliding carriage for moving said carriage according to changing beam-thread diameters.
- 15 2. In a knitting machine having a cam shaft, knitting needles, thread guides operated by the cam shaft, and having a warp beam: the improvement which includes a stationary frame mounted on the knitting machine; a driving shaft carried by said frame; a driven shaft carried by said frame; a gear connection between said driven shaft and the warp beam; a friction wheel on the driving shaft and a friction wheel 20 on the driven shaft engaged by the first mentioned friction wheel; a gravity actuated carriage for said first mentioned friction wheel; and means governed by the reduction in the diameter of the roll of thread on the beam for effecting the lowering of said carriage in proportion thereto, thereby governing the distance the beam is turned during each revolution of the crank shaft.
- 25 3. In a knitting machine wherein are provided knitting needles, thread guides, a cam shaft for operating the needles and thread guides, and wherein is provided a warp beam: a stationary frame mounted on the machine; a driven pair of vertical inter-gear shafts mounted in bearings on said carriage and operatively connected with said cam shaft, the operative connections including a changeable-speed power transmission mechanism; friction drive wheels vertically slideably mounted on said shafts; a driven shaft journaled in bearings on said frame; a friction driven wheel on each of said drive shafts with both sides 30 of which said first mentioned friction wheels engage; gear connections between said driven shaft and said warp beam; a carriage for said friction drive wheels slideably mounted in said frame and continuously tending to move in one direction to shift said friction drive wheels on said friction driven wheel; at least one rack carried by said carriage; at least one shaft rotatably mounted on said frame and having a pinion to engage said rack; a rack bar carrying a member engaging the beam thread and continuously tending to move 35 toward the axis of the beam; and an operative connection between said one shaft and said rack bar.
- 40 4. In a knitting machine having a cam shaft, knitting needles, thread guides, a beam and a constantly rotating shaft; the improvement which includes a support; a pair of parallel shafts rotatable in said support; meshing gears on said pair of shafts; a step-by-step power transmission including a variable-speed transmission mechanism between said constantly rotating shaft and one of said parallel shafts; friction wheels slideable on and rotatable with said parallel shafts; a third shaft mounted in said support; a friction disc on said third shaft; power transmitting connections between said third shaft and said beam; a sliding carriage for said friction wheels; a member for 45 resting on the thread of the beam and movable along a radius of the beam; and operative connections between said member and said sliding carriage for moving said carriage according to changing beam-thread diameters.
- 50 5. In a knitting machine having a cam shaft, knitting needles, thread guides, a beam and a constantly rotating shaft; the improvement which includes a support; a pair of parallel shafts rotatable in said support; meshing gears on said pair of shafts; a step-by-step power transmission including a variable-speed transmission mechanism between said constantly rotating shaft and one of said parallel shafts; friction wheels slideable on and rotatable with said parallel shafts; a third shaft mounted in said support; a friction disc on said third shaft; power transmitting connections between said third shaft and said beam; a sliding carriage for said friction wheels; a member for 55 resting on the thread of the beam and movable along a radius of the beam; and operative connections between said member and said sliding carriage for moving said carriage according to changing beam-thread diameters.
- 55 6. In a knitting machine having a cam shaft, knitting needles, thread guides, a beam and a constantly rotating shaft; the improvement which includes a support; a pair of parallel shafts rotatable in said support; meshing gears on said pair of shafts; a step-by-step power transmission including a variable-speed transmission mechanism between said constantly rotating shaft and one of said parallel shafts; friction wheels slideable on and rotatable with said parallel shafts; a third shaft mounted in said support; a friction disc on said third shaft; power transmitting connections between said third shaft and said beam; a sliding carriage for said friction wheels; a member for 60 resting on the thread of the beam and movable along a radius of the beam; and operative connections between said member and said sliding carriage for moving said carriage according to changing beam-thread diameters.
- 60 7. In a knitting machine having a cam shaft, knitting needles, thread guides, a beam and a constantly rotating shaft; the improvement which includes a support; a pair of parallel shafts rotatable in said support; meshing gears on said pair of shafts; a step-by-step power transmission including a variable-speed transmission mechanism between said constantly rotating shaft and one of said parallel shafts; friction wheels slideable on and rotatable with said parallel shafts; a third shaft mounted in said support; a friction disc on said third shaft; power transmitting connections between said third shaft and said beam; a sliding carriage for said friction wheels; a member for 65 resting on the thread of the beam and movable along a radius of the beam; and operative connections between said member and said sliding carriage for moving said carriage according to changing beam-thread diameters.

ROY C. AMIDON.
